DESIGN FOR A CONTAINER FOR FLAME COLORING MATERIAL

Florence J. De Coursey, Detroit, Mich.

Application April 26, 1943, Serial No. 110,051

Term of patent 7 years

To all whom it may concern:

Be it known that I, Florence J. De Coursey, a citizen of the United States, residing at Detroit, in the county of Wayne and State of Michigan, have invented a new, original, and ornamental Design for a Container for Flame Coloring Material, of which the following is a specification, reference being had to the accompanying drawing, forming part thereof.

In the drawing

Fig. 1 is a side elevational view of a container for flame coloring material showing my new design; and

Fig. 2 is a plan view showing the top of the container.

I claim:

The ornamental design for a container for flame coloring material, as shown.
